UNITED STATES PATENT OFFICE

WALTER S. MAYER, OF NEW BRIGHTON, PENNSYLVANIA, ASSIGNOR TO MAYER CHINA COMPANY, OF NEW BRIGHTON, PENNSYLVANIA, A CORPORATION OF PENNSYLVANIA

SUPPORTING DEVICE FOR POTTERY

Application filed June 15, 1928. Serial No. 285,636.

My invention relates to the art of burning pottery or ceramic ware in kilns, and particularly to an improved ware support of the crank type. It has in view to provide such a support of minimum size and weight and so constructed as to enable a plurality of them to be used in series with economy of space, while supporting each piece of ware in the kiln independently, with ample heat circulation space. Also, to provide for the ware a series of isolated stabilizing supporting points or edges, with interfitting engagement between adjacent supports, ensuring maintenance of position during use.

15 The present invention refers particularly to improved forms of supporting "points" or the like, and to the adaptation thereto and therewith of certain modified forms of construction in the main transverse supporting members. The improvements herein disclosed are related to the construction shown in the prior application of Benjamin D. Hardesty, Serial No. 278,372.

The construction of the device and its manner of use and advantages are more fully hereinafter described.

Referring to the drawings:

Fig. 1 is a plan view showing the relative arrangement of the supports and ware;

30 Fig. 2 is a vertical sectional view on the line II—II of Fig. 1;

Fig. 3 is a front view showing the interfitting connection between the supporting terminals of the main supports;

35 Fig. 4 is a perspective view of one of the point supports detached, as used in Figs. 1 and 2;

Fig. 5 is a plan view, partly broken away, showing a portion of the main support provided with a modified construction of seating socket and removable point therein;

Fig. 6 is a cross sectional view on the line VI—VI of Fig. 5;

Fig. 7 is a view similar to Fig. 5 showing 45 a further modified construction of supporting point;

Fig. 8 is a cross section on the line VIII—VIII of Fig. 7;

Fig. 9 is a view similar to Fig. 7 showing 50 a further modified construction;

Fig. 10 is a cross section on the line X—X of Fig. 9.

In utilizing supporting devices of the kind involved, it is desirable to interpose between each piece of ware and the next adjacent piece, a support which will be spaced away from the ware sufficiently far to avoid contact except at a minimum number of locations and of as limited area as possible. Also, to generally conform to the contour of 55 the ware and with ample transverse intervening space for circulation of the heating gases 60 of the kiln.

While the particular shape of the supporting device transversely may be varied to 65 adapt it approximately to the outline of the ware in cross section, it will be understood that the invention is not strictly limited to any particular extent of variation from a plane transverse area, or as to its size, dimensions, or shape.

One common form of ware is shown in the drawings, as a plate or dish 2, the middle portion of which is usually depressed below the surrounding rim or edge, and is ordinarily provided with the usual lower supporting rim, foot or bead 3 underneath.

Each of the series of supporting devices which carry a vertical series of ware pieces in the kiln, is made in skeleton form, of a general comparatively flat tripod construction 75 having three equilaterally arranged arms 4. These arms diverge from a middle flat portion 5, preferably provided with a middle circular or other shaped clearance opening 6, each arm sloping upwardly as at 7, and then extending downwardly in the form of a vertical terminal foot piece 8. Each such foot piece is adapted to rest upon the upper edge portion of the next lower support, and to provide, by its upper edge, a supporting bearing for the next upper support.

For the purpose of providing an interlock between the several pedestals 8, each is provided at its upper corner edge portion with a 85 socket 9, adapted to receive and interfit with a lower projecting correspondingly narrower projection 10.

Projection 10 fits into socket 9 with slight clearance, each socket being shouldered in- 100

wardly and at each side laterally so that when one support is placed upon another it will be held against lateral displacement, especially under the weight of the ware members 2 and the superimposed supports.

For the purpose of providing a point bearing at equally arranged positions annularly, and preferably just inside the foot extension 3, I provide the plural points 11 in the various arrangements shown. In the construction illustrated in Figs. 1 to 4 inclusive, these points extend upwardly at the terminals of radially extending arms 12 which meet and are integrally connected at the center, forming one continuous piece or spider. The bottom faces of the several arms, and of all three are on a common general plane, and of a width between their parallel sides adapting the complete three armed piece to be set downwardly within the depressed or socket portions 13 of each arm.

The depressed seats 13 extend radially as shown somewhat beyond the outer limits of the supporting piece, and are slightly wider, so that the piece may be easily set therein with slight clearance for adjustment in placing. As thus located, the points 11 engage against the under flat surface of the ware, as in Fig. 2, supporting it evenly at all positions when placed, without danger of tilting.

In the construction of Fig. 5, the arms 4 are provided at three equidistant locations with circular depressed seats 13^a, in which are mounted the circular flat bottom conical point members 11^a, with slight clearance as shown. By such arrangement the several supporting point members are located approximately in the desired position for similar supporting engagement with the ware, and at the proper height to effect space economizing and operative engagement therewith.

In the construction of Fig. 7, the arm 4 is similarly provided with a radially arranged V-shaped depression or socket 13^b, in which is set the diamond-shaped support 11^b, having a knife edge terminal, and of the same construction below and above its middle. By such construction and arrangement the support 11^b may be inserted within its snugly receiving seat, with slight longitudinal clearance as desired, and will present a bearing edge in the same general manner as that shown in the prior application referred to, with a double edge reversible feature.

In the construction of Fig. 9, the arm 4 is provided with a triangular depressed seat 13^c, in which is mounted the triangular point member 11^c, the sides and edges of which converge at the top, providing a single supporting point, in the same general manner as shown in Fig. 5.

The ware supporting points as thus made are composed of suitable refractory material as commonly utilized in the pottery art, and are simple in construction, cheap to man-

facture, and durable. Because of their three-point bearings, both as to the support of the ware and supporting connection with each other, as in Fig. 4, or when used separately, all of the supporting pieces are very easily assembled and taken apart, and provide continuous supporting equilibrium both as to themselves and their burden.

Due to their comparatively limited body section and weight, they have a corresponding limited heat absorptive value so that their removal from the kiln involves a minimum amount of heat subtraction therefrom. Their form contributes materially to the successful and economical operation of the kiln, both in manipulation, placement, and removal, while the interlocking construction of the main cross members 5 ensures stability and avoidance of accidental breakage.

The particular advantage in either of the herein disclosed improved supporting elements, adapted to be used in connection with the main transverse members 4, as disclosed, is in the provision of individual point supports for the ware, which reduce the liability of any abrasion or distortion to a minimum. In either of the forms shown, the definite placement of the interposed separating and supporting means is facilitated, while the point supporting devices themselves are comparatively simple and economical in manufacture and use.

It will be understood that the improvement, in either of the forms shown, may be made in various sizes, proportions, shapes, etc., to adapt it to any particular design or shape of ware, and that various changes or modifications may be made in its detail construction by the skilled mechanic, without departing from the scope of the following claims.

What I claim is:

1. A supporting device for pottery ware consisting of a transverse member having radially disposed arms provided with radially disposed holding sockets, and a one-piece removable support thereon having ware-engaging projections.

2. A supporting device for pottery ware consisting of a transverse member having radially disposed arms provided with radially disposed holding sockets, and an individual removable support thereon having ware-engaging projections.

3. A supporting device for pottery ware consisting of a transverse member having radially disposed arms provided with communicating radially disposed holding sockets, and a removable plural arm support insertible in said sockets and having upwardly extending point supporting terminals.

4. A supporting device for pottery ware consisting of a transverse member having radially disposed arms provided with radially disposed holding sockets, and an individual

supporting device therein having upwardly tapering terminal points.

5. In combination with a main transverse supporting bridge member having a series of depressed radial sockets on its upper face, a ware-supporting member having a plurality of flat bottom supporting arms provided with projections and seated in the sockets.

10. 6. In combination with a main transverse supporting bridge member having a series of depressed radial sockets on its upper face, a one-piece ware-supporting member having a plurality of radial flat bottom supporting arms provided with projections and seated in the sockets.

15. 7. In combination with a main transverse supporting bridge member having three radially extending arms each provided with a radially disposed depressed seat, a ware-supporting member engaging said seats and having a plurality of upwardly extending point devices.

20. 8. In combination with a main transverse supporting bridge member having three radially extending arms each provided with a radially disposed depressed seat, a triple armed support having a bottom face interfitting in said seats and provided with upwardly extending ware supporting points.

25. 9. A ware-supporting spider consisting of a one-piece member having a plurality of straight radially disposed parallel sided arms joined at the center having terminal upwardly projecting ware-supporting points conforming to a common level and a lower continuous flat bottom.

30. In testimony whereof I hereunto affix my signature.

40. WALTER S. MAYER.
